[57] CLAIM

The ornamental design for a emergency signal float, as
shown and described.

DESCRIPTION

FIG. 1 is a top plan view of an emergency signal float
showing my new design;

FIG. 2 is a side elevational view thereof;

FIG. 3 is a section taken along line 3—3 of FIG. 1
thereof;

FIG. 4 is a top plan view of a second embodiment
thereof;

FIG. 5 is a side elevational view thereof;

FIG. 6 is a section taken along line 6—6 of FIG. 4;

FIG. 7 is a reduced bottom plan view of FIG. 4;

FIG. 8 is an enlarged fragmentary section view taken
along line 8—8 of FIG. 4 illustrating the shape of the
snap-on pegs;

FIG. 9 is a perspective view of the first embodiment
thereof;

FIG. 10 is a perspective view of the second embodiment
thereof.
